[57] CLAIM

The ornamental design for a cap with lights, as shown and described.

DESCRIPTION

FIG. 1 is a front perspective view of a cap with lights showing my new design;

FIG. 2 is a rear perspective view thereof;

FIG. 3 is a side elevational view thereof taken from the right of FIG. 2, the opposite side being a mirror image thereof;

FIG. 4 is a top plan view thereof; and,

FIG. 5 is a bottom plan view thereof.
